UNITED STATES PATENT OFFICE

CHARLES D. EVANS, OF JERSEY CITY, NEW JERSEY

SNAP HOOK

Application filed September 30, 1929. Serial No. 396,256.

This invention relates to certain improvements in snap hooks; and the nature and objects of the invention will be readily understood by those skilled in the art in the light of the following explanation and detailed description of the accompanying drawings illustrating what I, at present, consider to be the preferred embodiments or mechanical expressions from among various other forms, arrangements, combinations and constructions of which the invention is capable within the spirit and the scope thereof.

The invention is more particularly directed to those types of snap hooks which embody a freely movable, spring-actuated member or tongue normally closing the hook and which can be depressed or swung to position opening the hook to permit of attaching and detaching same. With these types of snap hooks, considerable difficulty is experienced in preventing the hook closing member or tongue from being inadvertently or accidentally depressed or forced inwardly to position opening the hook and allowing the hook to free itself or become disengaged from a member to which it has been attached.

A general object of the invention is to provide locking mechanism for such types of hooks through the medium of which the hook-closing member or tongue can be readily secured and held against hook-opening movement, or can be released for operations to open the hook. Another object of the invention is to provide locking mechanism for a hook of this type which will be of simple mechanical construction and will not materially add to the weight or over-all dimensions of the hook; which will be of a construction readily manufactured at comparatively low cost, and which will be efficient in operation and use to permit of quickly and easily releasing or securing the hook-closing member or tongue.

A feature of the invention resides in the provision of such a locking mechanism which embodies a securing or locking member carried by the hook-closing member or tongue and swingable laterally to and from position interposed between the tongue and adjacent hook structure to secure and lock the

tongue into hook-closing position against depression or inward hook-opening movement; and, further, which embodies a manually operated member for releasably securing the tongue-locking member in tongue securing or locking position against movement.

With the foregoing and certain objects and results in view which will be readily apparent from the following explanation, the invention consists in certain novel features in construction and in combination and arrangement of parts as will be more fully and particularly referred to and specified hereinafter.

Referring to the accompanying drawing, in which similar reference characters refer to corresponding parts throughout the several figures thereof:

Fig. 1 is a view in side elevation of a snap hook of my invention, embodying one form of locking mechanism therefor, such mechanism being shown in locked position securing the hook-closing member or tongue against opening.

Fig. 2 is a view similar to Fig. 1 with the locking mechanism released for swinging to position to permit of depressing the tongue and opening the hook.

Fig. 3 is a plan view of the snap hook of Fig. 2.

Fig. 4 is a plan view of the hook of Figs. 1 to 3, with the locking mechanism swung laterally to position releasing the spring tongue for movement to open the hook.

Fig. 5 is a perspective view of the hook of Fig. 1, showing the locking mechanism in unlocked, spring-tongue releasing position, with the spring tongue depressed to hook-opening position.

Fig. 6 is a view in side elevation of another form of snap hook locking mechanism of my invention, portions of the hook being shown in vertical section.

Fig. 7 is a view of the hook of Fig. 6, showing the locking mechanism in its laterally swung, unlocked position with the spring tongue depressed to hook-opening position.

Fig. 8 is a view in top plan of the hook.

of Figs. 6 and 7, with the locking mechanism in laterally swung, tongue-releasing position.

The invention is disclosed in the accompanying drawings as applied to one form of snap hook of well known and widely used construction, but it is to be understood that the invention is not limited or restricted to use with this particular type of hook, as the invention is of general application to snap hooks of various other types and construction, as well as to hooks of other than the so-called "snap" hooks. Several forms of which the invention is capable are presented herewith, purely by way of example and not of limitation, for the purpose of explaining and bringing forth the principles and various features of the invention to enable those skilled in the art to understand the same. However, it is not intended to limit the invention to the exact forms here shown as the invention contemplates and includes various other forms and arrangements embodying the broad principles and various features of the invention.

In the preferred form of the invention illustrated in Figs. 1 to 5, a snap hook comprising the hook body or shank 10 terminating in the hook bill 11 at one end and, at the other end, provided with any suitable attaching means, such as the swivel shackle 12, is disclosed. A hook-closing member or tongue 14 is suitably mounted and secured to the body of shank 10 at the end thereof, opposite the hook bill, and extends forwardly and outwardly across the hook shank 10 to and engages the inner side of the free or outer end of the hook bill. This member or tongue 14 is in the present example, although not so limited, formed of spring material and is mounted so as to normally extend across and close the hook, as will be clear by reference to Figs. 1 and 2 of the drawing. The operation of this spring tongue is well understood in the art, the hook being opened by depressing the tongue and moving the same inwardly toward the hook shank 10. From its depressed hook-opening position, the tongue springs back to normal hook-closing position upon the release or removal of the depressing hook-opening forces therefrom.

In accordance with the invention, a tongue securing or locking member 15 is carried by the spring tongue 14, and in tongue-locking position is interposed between and engages the hook shank 10 and the inner side of the tongue, holding and securing the tongue in hook-closing position against depression or inward hook-opening movement. In the present example, this locking member 15 is in the form of a block having a projection 16 at its forward and outer, or tongue-engaging end, by which it is pivotally connected with the forward end of the tongue 14 through the medium of a pivot pin 17, the locking mem-

ber extending from this pin a distance along the under side of the locking tongue and between the tongue and the hook shank. The hook bill 11 is provided with a transverse bore or hole 18 therethrough, adjacent to end of the hook bill, which bore receives the outer end of the locking member pivot pin 17 with the tongue in hook-closing position, as shown particularly in Figs. 1 and 2 of the drawing. The locking member 15 is laterally swingable on the pin 17 to the position extending laterally from the hook, as shown in Figs. 4 and 5. In this laterally extended position the member 15 is removed from between the tongue and hook shank 10 and lies so out of the path of inward movement of the tongue 14 so as to permit free depression or inward swinging movement of the tongue to hook-unlocking position. It is to be noted that, due to the projection 16 of member 15 and the pivotal connection of the member to the end of the tongue through this projection, when the member is swung laterally from the hook an unobstructed space is provided between the projection and the hook shank, which permits of free and unobstructed inward swinging movement of the tongue carrying the member 15.

When it is desired to lock the hook, the member 15 is swung inwardly to position interposed between tongue 14 and the hook shank, thereby locking the tongue against depression or inward opening movement. To release or unlock the hook-closing member or tongue 14, the locking member 15 is swung on pin 17 to the laterally extended position of Fig. 4 and the tongue is then depressed or swung inwardly, carrying member 15 with it, to the hook-opening position shown in Fig. 5 of the drawing. Upon release of tongue 14 in hook-opening position, the tongue springs outwardly to closed position and the member 15 is then swung inwardly to its tongue-securing and locking position interposed between the tongue and the hook shank 10.

The invention provides, further, for locking or releasable means securing the member 15 in position interposed between the hook shank and the tongue for holding the latter in hook-closing position. In carrying out this feature of the invention in the form shown in Figs. 1 to 5, a disc or circular plate 19 is rotatably mounted at one side of the member 15 on a stud or pin 20 fixed transversely in and extending through the member 15. This locking disc 19 is cut away at one side to provide the flattened portion 19a so that when the disc is rotated to the position shown in Fig. 2, the member 15 can be freely swung outwardly from within the hook without obstruction by or interference from the locking disc. The inner side of the hook shank 10 is formed with a slot or groove 21 therein and disposed longitudinally thereof

in alignment with the locking disc 19 when the member 15 is in tongue-securing position. When the member 15 is in tongue-holding position, the disc 19 lies in alignment with 5 groove 21 and by manually rotating or turning this disc from its position shown in Fig. 2, the disc is moved to position extending down into groove 21, as clearly shown by Fig. 1, and thereby locks member 15 in tongue- 10 holding position against lateral swing. The diameter of the disc 19 is such that it extends across the adjacent edge of the tongue 14 and thereby provides a stop, preventing lateral swinging of member 15 in other than the direction toward the side of the hook at which 15 the groove 21 is disclosed.

By the foregoing construction and arrangement therefor, the tongue-holding member is readily locked and secured against inadvert- 20 ent lateral swing when in tongue-holding position, by the locking disc 19 engaged in the hook shank groove 21. The member 15 is readily released and unlocked for lateral swing to permit of hook-opening movement 25 of the tongue, by rotating the locking disc 19 until the flattened portion thereof lies substantially parallel to the hook shank and removed from the groove 21.

A modified form of the invention is dis- 30 closed in Figs. 6 to 8 of the drawing, in which form in place of the locking disc 19 and hook shank groove 21, a locking screw or pin 22 is provided which, in the present instance, is threaded transversely through the hook shank 10 and extends inwardly a distance therebeyond at the inner side of the hook shank and in the path of movement of the tongue-securing member 15. The tongue-se- 35 curing member 15 is provided with a bore or socket 23 on its inner side for alignment with and receiving the extended end of the lock- 40 ing screw 22. In the operation and use of this form of the invention, with the locking member 15 in tongue-holding and securing position shown in Fig. 6, the screw 21 extends into the member socket or bore 23 and se- 45 cures and holds the member 15 against lateral swing. When it is desired to unlock and release member 15 for swinging to position 50 allowing opening movement of tongue 14, the locking screw 22 is moved outwardly to the position shown in Fig. 7, removed from socket 23 and thus allowing lateral swing of member 15 to the position shown in Figs. 7 55 and 8 for hook-opening movement of the tongue 14.

In the foregoing manner, the invention provides for the efficient and practical locking of hooks of the "snap" and other types to 60 prevent accidental opening thereof when in their locked, attached position. The width of a hook is not materially increased by the design and construction of the invention, due to the location in hook-closing position of the locking mechanism substantially within

and between the confines of the hook structure. The locking mechanism is such that it can be very readily and quickly manually operated to release and to lock the hook-opening and closing member, yet is so arranged and constructed as to practically eliminate possibility of inadvertent operation thereof to unlock the hook-closing member. 70

It is also evident that various changes, modifications, substantiations and variations 75 might be resorted to without departing from the spirit and the scope of my invention, hence I do not wish to limit myself to the exact and specific disclosures hereof.

Desiring to protect my invention in the 80 broadest manner legally possible, what I claim is:

1. In a snap hook, including a spring hook-closing tongue, a locking member pivotally carried by said tongue and swingable independently thereof to and from position interposed between the tongue and hook and securing the tongue in hook-closing position. 85

2. In a snap hook, including a spring tongue normally in hook-closing position, a locking member pivotally mounted and disposed at the inner side of said tongue and swingable to and from position interposed between the tongue and the hook. 90

3. In a hook, a pivotally mounted hook-closing member inwardly swingable from closed position to position opening the hook, and a locking member normally interposed between the hook and said closing member to secure the latter in closed position, against inward swinging to hook-opening position, the said locking member pivotally mounted and swingable laterally of the hook and hook closing member to position permitting inward swinging of the hook-closing member. 95

4. In a snap hook, a tongue for opening and closing the hook, a member pivotally mounted on the inner side of said tongue and disposed and engaged between the tongue and the hook to secure the tongue in hook-closing position, and the said member swingable outwardly to position extended laterally from the tongue and removed from position between the tongue and hook to permit the tongue to open the hook. 100

5. In a hook, a tongue normally closing the hook and inwardly swingable to position opening the hook, a member pivotally mounted on the tongue disposed and engaged between the inner side of the tongue and the opposite portion of the hook to secure the tongue in hook-closing position against inward swinging, said member swingable outwardly from between the tongue and hook to position permitting inward swinging of the tongue to hook-opening position, and means for releasably locking said member in tongue-securing position. 115

6. In a hook, a hook closing tongue inwardly swingable from hook closing position to 120

position opening the hook, and a member normally positioned at the inner side of and interposed between the tongue and the hook and maintaining the tongue in closed position against inward swinging, the said member movable to position removed from the path of and releasing the tongue for inward swinging to open the hook.

7. The combination with a hook having a closing tongue inwardly swingable to position opening the hook, of a member movable to and from position engaged between the tongue and the hook and interposed in the path of inward swinging of the tongue to hold the tongue in hook closing position against inward swinging.

8. In a hook, a hook closing tongue inwardly swingable from closed position to hook opening position, a member interposed between the tongue and hook at the inner side of the tongue to secure the tongue in closed position against inward hook opening swinging, and said member pivotally mounted and laterally swingable to position releasing said tongue for swinging to hook opening position.

9. In a hook, a hook closing tongue inwardly swingable from closed position to hook opening position, a member movable to position at the inner side of said tongue to hold the tongue against inward swinging, said member movable from tongue holding position to position releasing the tongue for inward swinging to open the hook, and a movable locking member for releasably locking said member in position holding the tongue in hook closing position.

10. In a hook, a spring pressed tongue in normal position closing the hook, said tongue swingable inwardly under pressure to position opening the hook, and a member pivotally mounted on said tongue and movable independently thereof to and from position bearing against the inner side of said tongue to secure the tongue against inward hook opening swinging.

11. In a hook, a tongue for opening and closing the hook, said tongue inwardly swingable from hook closing to hook opening position, a tongue holding member extending between the inner side of the tongue and the opposite side portion of the hook to hold the tongue in closed position against inward swinging to open the hook, said member provided with a supporting arm extending therefrom adjacent and pivotally mounted on the under side of the tongue at a point spaced from the member, and said member laterally swingable with said arm to and from position removed from and releasing the tongue for inward swinging to open the hook.

Signed at Jersey City, county of Hudson, New Jersey, this 26th day of September, 1929.

CHARLES D. EVANS.
